(57) **CLAIM**

The ornamental design for a slider for slide fastener, as shown and described.

DESCRIPTION

FIG. 1 is a perspective view of the front, bottom and right side of a slider for slide fastener, showing our new design;

FIG. 2 is a front view thereof;

FIG. 3 is a rear view thereof;

FIG. 4 is a right side view thereof, the left side view being a mirror image thereof;

FIG. 5 is a top plan view thereof; and,

FIG. 6 is a bottom view thereof.
